UNITED STATES PATENT OFFICE.

WYNFORD BRIERLEY, OF NELSON, ENGLAND.

APPARATUS FOR SIGNALING ON RAILWAYS.

SPECIFICATION forming part of Letters Patent No. 628,300, dated July 4, 1899.

Application filed January 6, 1898. Serial No. 665,811. (No model.)

To all whom it may concern:

Be it known that I, WYNFORD BRIERLEY, a subject of the Queen of Great Britain and Ireland, residing at Nelson, in the county of 5 Lancaster, England, have invented new and useful Improvements in and Connected with Apparatus for Signaling on Railways, of which the following is a specification.

The principal object of the present invention is to construct an efficient railway signaling apparatus to give both an audible and a visible signal on the engine or train as to the position of the semaphore-signal, whether it is at "danger" or at "safety," and also to provide specially-suitable signals on the engine or train and a special contact-bar (and adjuncts therefor) on the permanent way.

In carrying out one feature of my invention I prefer to avail myself of the type of railway signaling appliances illustrated in my application for patent, Serial No. 664,099, and that form of it in which a swinging lever is mounted on the engine or other suitable part of the train in such a position as to come into contact with a suitable projection upon the permanent way, this projection being movable and operated by the signalman or otherwise as the line is clear or blocked. This swinging lever is connected to apparatus constructed to operate a bell or other alarm on the train, and the lever is preferably held in normal central position by two reversed springs, so that the lever will act equally whether the train is moving in one direction 35 or the other, and this without undue shock or injury. The controlling projection on the permanent way can be operated by the working of the semaphore.

In the accompanying drawings, Figure 1 is 40 a vertical section of the lever-box on the engine or other suitable part of the train. Fig. 1^a is a sectional view on the line 1 1, Fig. 1. Fig. 1^b is a sectional view on the line 2 2, Fig. 1. Figs. 2, 2^a, 3, 3^a, and 4 are views of the 45 improved electrical signaling appliance on the engine. Figs. 5, 6, and 7 are views of my improved contact-bar upon the permanent way, and Figs. 5^a and 6^a are views of a modification.

50 Referring to Figs. 1, 1^a, and 1^b, it will be

observed that I construct the operating-lever *a* and its adjuncts (upon the engine or other suitable part of the train) in duplicate to effect the operation of corresponding signals upon the engine. In the box *A*, I fix two shafts 55 *a'* and *a¹⁰*, the first carrying the pendent lever *a* and the second carrying the pendent lever *a⁰*. The levers *a* *a⁰* are held in their normal central positions (as in my application Serial No. 664,099) each by a pair of reversed spiral 60 springs *c* *c'*, *c⁰* *c¹⁰*, or equivalent device, Figs. 1 and 1^b. Each shaft *a'* *a¹⁰* is provided with a cam *a²*, which upon the swinging of the lever in either direction causes springs *a³* to come into contact with the springs *a⁴*, Fig. 1^a, 65 or *a⁴⁰*, Fig. 1, to close the circuits through the wires *a⁵* and *a⁶* or *a⁵⁰* *a⁶⁰*, as the case may be. These wires *a⁵* *a⁶* and *a⁵⁰* *a⁶⁰* are connected up to the two sets of electromagnets in the signaling-box *D* on the engine. This box *D*, 70 as shown in Figs. 2, 2^a, and 4, is provided with an audible signaling gong or bell *d*, common to both danger and safety signals. The visible danger-signal is a disk *d'* on a 75 swinging lever *d³*, Fig. 2, and is moved to a position where it will show through an opening *D'* in the face of the box *D*, Figs. 2^a and 3, when the line is blocked or the semaphore-signal is at "danger." The visible safety-signal is a disk *d²*, Fig. 2, on a lever *d⁴* and 80 adapted to be moved behind an opaque spaced shutter *D²*, Fig. 2^a, in the front of the casing or box *D*, so as to show the letters "Safe" or their equivalent through the spaces between the opaque strips of *D²*, when the line 85 is clear or the semaphore-signal is at "safety."

In the drawings, Figs. 2 and 2^a, for the sake of illustration, show both the danger-signal and the safety-signal in the visible positions.

The lever *d³* is so weighted that when it 90 stands in the position shown by dotted lines in Fig. 2 and by full lines in Fig. 3^a it is held in that position by the end of a spring-lever *d⁵*, which forms part of the armature of an electromagnet *d⁶* in circuit with the wires *a⁵* *a⁶* from the lever *a*. When this magnet *d⁶* is excited by the completion of the current by the rocking of this lever *a*, the armature *d⁵* is raised and releases the lever *d³*, which falls into the position shown in full lines in Fig. 100

2 and into contact with a spring d^7 . The clapper d^8 , carried by the armature d^5 , at the same time rings the bell d .

The circuits are as follows: The wire a^5 is connected through the binding-post 5 and wire 7 to the armature-lever d^5 , which is normally in contact with the insulated back-stop d^{16} . This latter is connected to the coils of the operating-electromagnet d^6 , Figs. 2 and 3^a, by the wire 8, and these coils are connected by the conductor 9 and back-stop 6 and conductors 10 and 11 to one terminal of the battery E. The other terminal of the battery has the conductor a^6 connected to it.

15 The lever d^3 is electrically connected through its supporting-post d^{31} and frame d^{32} to the armature-lever d^5 , and thence through back-stop d^{16} , the coils d^6 , and wires 9, 10, and 11 to one terminal of the battery E. The spring d^7 is connected through the insulated post d^{17} and wire d^{18} to the other terminal of the battery E.

Both the described circuits are normally open; but when the movement of the lever a 25 closes the circuit through a^5 a^6 at a^3 a^4 and through the coils of the electromagnet d^6 the bell rings and the visible signal d' falls from the position shown in Fig. 3^a to the position shown by full lines in Fig. 2. This fall of 30 the signal d' causes the lever d^3 to make contact with the spring d^7 , and so closes the circuit from d^{18} , d^{17} , and d^7 through d^{31} d^{32} , armature d^5 , back-stop d^{16} , coils d^6 , and wires 9, 10, and 11 to the battery, producing a continuous ringing of the bell until the engineer pushes upward the button d^8 to lift the lever d^3 and its disk d' up into the position shown by dotted lines in Fig. 2, to be caught by the projection on the armature-lever. The spring 40 d^7 then returns and breaks the connection. This spring d^7 performs several functions. It serves as contact-maker for continuous alarm, a support for the indicator or signal when shown, and a replacer of the said signal. Furthermore, supposing that at any time 45 it is desired to test the battery and the signal generally before starting on a journey, the engine-driver or an inspector can by pushing the spring d^7 up to make contact with the lever d^3 complete the electric circuit, and if the bell rings properly the apparatus is in order. This danger-signal may be used with the single form of lever a , (shown on Figs. 2, 3, and 4 of the drawings accompanying the 50 United States application, Serial No. 664,099, above mentioned;) but I prefer to use it with the double arrangement already referred to, so that the bell d may serve also to give a signal (though not a continuous one) when the 55 semaphore signal is at "safety" or "line clear."

Referring now to the safety-signal part of the device, the circuit is from one terminal of the battery E, Fig. 2, through the wire 11, binding-post 60, and wire 12 to the coils of the operating-electromagnet d^{10} , thence to the

frame and armature d^{13} , wire 13, binding-post 50, and conductor a^{50} to the contacts a^{40} , Fig. 1, and wire a^{60} to the battery. One of the pole-pieces d^{11} of this magnet d^{10} is extended 70 and cranked, as shown, so as to attract a second armature d^{12} , as well as the armature d^{13} , to which the clapper d^{80} is fixed. This armature d^{12} is fixed or fitted to a depending lever d^4 , held in place by two reversed springs 75 d^{15} , acting and disposed in a similar manner to the springs c c' , above described. The lever d^4 carries the disk or plate d^2 , on which the letters "Safe" or any equivalent devices are marked in such a manner as (when the 80 armature d^{12} is not attracted) to be concealed by the opaque parts of the spaced shutter D^2 . As soon, however, as the armature is attracted the bell d is sounded and the letters or devices appear in sight until the second lever 85 a^0 has ceased to vibrate sufficiently to complete the necessary circuit.

The next part of my invention relates to the contact-bar for deflecting either of the levers a^0 , as desired, according to the positions of 90 the semaphore-signal. For this purpose I use a rocking lever, Figs. 5, 6, and 7, with two ends b b^X similarly formed, but one, b^X , heavier than the other, b , each end forming a contact-bar, as required. The lever b b^X is 95 mounted on a shaft b^6 , carried by suitable brackets b' , fixed in such a position that the path of one lever a is above b and that of the other a^0 is above b^X . The lever b b^X is moved by a lever b^5 on the shaft b^6 , the lever b^5 being connected by a wire, rod, chain, or cord b^2 , Fig. 5, to the usual weighted lever of the semaphore-signal in such a manner that when the semaphore is raised to "danger" the part b of the lever is raised, as shown, and when 100 lowered to "safety" the part b^X is raised by the pulling of b^2 in the direction of the arrow, Fig. 5.

Figs. 5^a and 6^a show how the lever b b^X may be worked from several semaphore-signals by 110 using a corresponding number of levers—say b^5 b^7 b^8 —and forming in each lever a quadrant-shaped recess b^{XX} , in which a key x , fixed in the shaft b^6 , can work, and thus any one of the levers b^5 b^7 b^8 —say b^5 —can move 115 the lever b b^X without interfering with or moving the other levers—say b^7 b^8 . The part b^X of the lever being heavier than b will keep the engine-signal always at "danger" unless withdrawn to "safety." I further provide 120 spring stops or buffers b^9 b^{10} for each portion of the rocking bar b b^X , so that thus the working part of the latter cannot get out of place by being pulled or dropped too far. Another feature of this weighted rocking bar b b^X is 125 that it can be connected to a gate at a level crossing and warn the engineer whether the gate is open or closed.

I claim as my invention—

1. In a railway signaling apparatus, the 130 combination of two electric signals on an engine with two spring-levers also on the engine

or train, and connections between the levers and signals, with a rocking contact-bar on the permanent way, having two contact-arms, one adapted to deflect one of said levers when the line is clear and the other arm to deflect the other lever when the line is blocked, all substantially as described.

5 2. The combination of two signaling-electromagnets and their respective armatures carrying clappers with a gong or bell common to the two clappers, and visible signals controlled by said electromagnets, all within an inclosing case, substantially as described.

10 3. The combination of the electromagnets and armature of a signaling apparatus with a signal-lever controlled by said armature and

a push-button adapted to act on said signal-lever and also to close the circuit for testing, substantially as described.

4. In a railway signaling apparatus, the 20 combination of a pair of levers on the engine or train to control signals thereon with a weighted rocking bar on the permanent way, having two contact-arms for the respective levers, substantially as described.

25 In testimony whereof I have signed my name to this specification in the presence of two subscribing witnesses.

WYNFORD BRIERLEY.
